United States Patent Office

Des. 215,470
Patented Sept. 30, 1969

215,470

SUGAR BOWL

Gerald Gulotta, New City, N.Y., assignor to Block China
Company, New York, N.Y., a partnership

Filed Dec. 16, 1968, Ser. No. 15,004

Term of patent 14 years

Int. Cl. D7—01

U.S. Cl. D44—15

I claim:

The ornamental design for a sugar bowl, substantially as shown.
